LIGHTING FIXTURE

Edwin F. Guth, Florissant, Mo.

Application February 17, 1947, Serial No. 728,975

6 Claims. (Cl. 240—51.11)

1

This invention relates to lighting fixtures and more particularly to lighting fixtures for fluorescent lamps.

Among the object of this invention are the provision of an improved lighting fixture which is easy to maintain and to clean; the provision of a lighting fixture the parts of which are more resistant to breakage in transit; the provision of a lighting fixture which decreases accidents during maintenance operations; and the provision of a lighting fixture of an attractive appearance which is of simple construction and is inexpensive to manufacture. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is an isometric view of a fixture constructed in accordance with the present invention;

Fig. 2 is an end elevation viewed from the righthand end of Fig. 1, being partly sectioned on line 2—2 of Fig. 1;

Fig. 3 is an isometric view of a diffusing panel;

Fig. 4 is a fragmentary view similar to the sectional part of Fig. 2, but on an enlarged scale;

Fig. 5 is a view similar to Fig. 4 but showing some of the parts in alternative position; and,

Fig. 6 is a section taken on line 6—6 of Fig. 4.

Similar reference characters indicate corresponding parts throughout the several views of the drawings.

Referring now to the drawings, numeral 1 indicates a lamp support comprising an outer case, channel or top housing which supports the usual electrical starter apparatus indicated generally at 3. Case 1 has end walls 5 and side walls at 7. The end walls are formed with downwardly convergent dihedral lower edges. Sockets 9 at either end removably support tubular fluorescent lamps 11. Attached to end walls 5 adjacent their apexes at a median line on their lower edges are channel-shaped support stops 13. The end walls 5 are bent over along their lower edges to form stop flanges 15. Stops 13 act as panel supports and cooperate with flanges 15 to position light diffusing and light transmitting panels 17 in a dihedral relationship, supporting the panels by their inner corners. The panels are preferably

constructed of glass or plastic. Along one edge 19 of panels 17 are metal reinforcing strips 21. Strips 21 are formed as channels with the top bent back to form wings 23 (see Figs. 4—6). Wings 23 do not extend the entire length of supporting channel 21 but terminate adjacent to reinforcing and supporting channels 25 along either side of panels 17. Channels 21 and 25 are cemented to panels 17 in any of the customary manners. One end 27 of channels 25 is bent to form ears in each of which is an opening 29. Opening 29 receives one end of a hinge strap or link 31 while openings 33 and 35 in side walls 7 receive the other end of strap 31.

End 37 of hinge strap 31 is formed as a roll permanently to hold end 27 while end 39 of strap 31 is formed as a square hook for easy attachment and detachment of the panel 17 assembly to or from top housing 1. Opening 35 is formed sufficiently large so that end 39 of hinge strap 31 can enter or be removed therethrough. Opening 33 permits rotation of hinge strap 31 (see Fig. 5).

The fixtures of the present invention may be easily and quickly assembled and disassembled. Thus diffusing panels 17 may be separated from top housing 1 merely by slipping panel 17 out of stops 13 and lifting ends 39 of hinge straps 31 out through openings 35. Assembly is easily and quickly accomplished by reversing the process. This permits panel 17 to be shipped separately from the rest of the fixture to minimize danger of breakage. Such danger is further minimized by channels 21 and 25 which strengthen diffusing panels 17 during transportation and during use.

One of the important features of the present fixture is that it may be easily and quickly cleaned without removing panels 17 from the fixture. Moreover, repairs may be carried out and lamps replaced without removing panels 17 from the fixture. This is accomplished by reason of the construction and operation of hinge straps 31 and cooperating mechanism.

A cleaning operation, for example, is quickly and easily carried out. Fig. 4 shows the position of the parts when the fixture is in use. If now it is desired to clean diffusing panel 17 or otherwise service the fixture, panels 17 are moved out of stops 13 either manually or preferably with a simple tool such as illustrated at 41. Essentially tool 41 is an angle iron 40 attached to a stick 42 and with it panel 17 is contacted along the median line of the fixture and moved, as shown in Fig. 5, until edge 19 clears stop 13. If

panel 17 is now released it will rotate to the dotted line position shown in Fig. 5, thereby permitting easy access to panel 17 itself with a cleaning device, or easy access to the interior of the fixture for repair or replacement of parts. Since panel 17 will remain suspended, danger of dropping it is negligible and there is no need to deposit it in some place where it might be damaged or damage others.

Once the cleaning operation, etc., is finished, edge 19 of panel 17 is again grasped with tool 41 and panel 17 is permitted to slide back into place against stops 13. During this operation channels 15 serve as guides for panels 17.

Side walls 7 are preferably cut away at 43 to receive the round end 37 of hinge strap 31 and to permit ear 27 to lie in the same plane as side walls 7 when the fixture is in its Fig. 4 position. Hinge straps 31 do not project from side walls 7 far enough to be objectionable.

Side walls 7 need not extend clear across the fixture but it is sufficient if they are large enough to support hinge straps 31, diffusing panels 17 and associated mechanism.

In view of the foregoing it will be apparent that the fixture of the present invention may be easily and quickly assembled or disassembled and that quick access may be had to the interior for cleaning or repair. Moreover the present fixture is attractive, easily operated and relatively safer because diffusing panels 17 need not be removed from the fixture. Moreover, diffusing panels 17 may be shipped separately and danger of breakage is substantially decreased by the presence of channels 21 and 25.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A ceiling fixture for fluorescent lamps, comprising a lamp support having end walls formed with downwardly convergent dihedral lower edges, a pair of light-transmitting panels carried by the support for movement between a raised position wherein they extend in dihedral relationship under the support from one end wall to the other and a lowered position extending downward from the support, panel supports adjacent the apexes of the end walls for supporting the panels by their inner corners in said raised position, each panel being linked to the support by means of links pivotally connected at their upper and lower ends to the support and panel respectively, whereby the panel may be moved laterally outward from its raised position to clear its said corner supports and then swung downward to its said lowered position.

2. A ceiling fixture for fluorescent lamps, comprising an open-bottomed housing having side and end walls, the latter having downwardly convergent dihedral lower edges, a pair of light-transmitting panels carried by said housing for movement between a raised position wherein they extend in dihedral relationship under the housing closing its open bottom, and a lowered position extending generally downward from the side walls of the housing, panel corner supports adjacent the apexes of the end walls for supporting the panels by their inner corners in said

raised position, each panel being pivotally connected to the housing by means of links pivotally connected at their upper and lower ends to the respective side wall and the panel, whereby the panel may be moved laterally outward from its raised position to clear its said corner supports and then swung downward to its said lowered position.

3. A ceiling fixture for fluorescent lamps, comprising an open-bottomed housing having side and end walls, the latter having downwardly convergent dihedral lower edges, a pair of light-transmitting panels carried by said housing for movement between a raised position wherein they extend in dihedral relationship under the housing closing its open bottom, and a lowered position extending generally downward from the side walls of the housing, panel corner supports adjacent the apexes of the end walls for supporting the panels by their inner corners in said raised position, each panel being pivotally connected to the housing by means of links detachably pivoted at their upper ends to the outside of the respective side wall and pivotally connected at their lower ends to the panel, whereby the panel may be moved laterally outward from its raised position to clear its said corner supports and then swing downward to its said lowered position, or detached from the housing.

4. A ceiling fixture for fluorescent lamps, comprising an open-bottomed housing having side and end walls, the latter having downwardly convergent dihedral lower edges, a pair of light-transmitting panels carried by said housing for movement between a raised position wherein they extend in dihedral relationship under the housing closing its open bottom, and a lowered position extending generally downward from the side walls of the housing, panel corner supports adjacent the apexes of the end walls for supporting the panels by their inner corners in said raised position, each panel being pivotally connected to the housing by means of links having hooks at their upper ends detachably and pivotally engaged in openings in the side walls from the outside of the latter and pivotally connected at their lower ends to the panel, whereby the panel may be moved laterally outward from its raised position to clear its said corner supports and then swung downward to its said lowered position, or detached from the housing.

5. A ceiling fixture for fluorescent lamps, comprising an open-bottomed housing having side and end walls, the latter having downwardly convergent dihedral lower edges, a pair of light-transmitting panels carried by said housing for movement between a raised position wherein they extend in dihedral relationship under the housing closing its open bottom, and a lowered position extending generally downward from the side walls of the housing, each panel having reinforcing members at its ends, said members being provided with ears extending upward from the upper side of the panel, panel corner supports adjacent the apexes of the end walls for supporting the panels by their inner corners in said raised position, each panel being pivotally connected to the housing by means of links pivotally connected at their upper and lower ends to the respective side wall and the ears of the respective reinforcing members, whereby the panel may be moved laterally outward to clear its said corner supports and then swung downward to its said lowered position.

6. A ceiling fixture for fluorescent lamps, com-

prising an open-bottomed lamp housing having side and end walls, the latter having inwardly flanged downwardly convergent dihedral lower edges, a pair of light-diffusing panels carried by said housing for movement between a raised position wherein they extend in dihedral relationship under the housing closing its open bottom, and a lowered position extending generally downward from the side walls of the housing, each panel having reinforcing channels embracing its ends, said channels being provided with ears extending upward from the upper sides of the panel, each panel also having reinforcing strips extending the length of its edge which is innermost when the panel is in raised position, panel corner supports comprising channel-shaped members adjacent the apexes of the end walls which open laterally outward receiving the inner corners of said panels in their raised position, each panel being pivotally connected to the housing by 20 means of double-acting hinge members detach-

ably pivotally connected at their upper ends to the respective side wall and pivotally connected at their lower ends to the ears of the respective reinforcing channels, whereby the panel may be moved laterally outward to clear its said corner supports and then swung downward to its said lowered position, or detached from the housing.
